UNITED STATES PATENT OFFICE.

JOSEPH DEHOUCK, OF THIELT, BELGIUM.

AEROPLANE ASSURING AUTOMATICALLY THE LATERAL AND LONGITUDINAL STABILITY.

Application filed August 17, 1921. Serial No. 493,109.

(GRANTED UNDER THE PROVISIONS OF THE ACT OF MARCH 3, 1921, 41 STAT. L., 1313.)

To all whom it may concern:

Be it known that I, JOSEPH DEHOUCK, a subject of the King of the Belgians, residing at Thielet, Belgium, have invented an Improved Aeroplane Assuring Automatically the Lateral and Longitudinal Stability, for which I have filed applications in Great Britain, 118,049, Jan. 8, 1918; France, 84,005, June 9, 1916; Belgian, Patent 265,003, Feb. 2, 1914, and of which the following is a specification.

The object of the present invention is to construct an improved aeroplane having automatic stability in two directions, the one longitudinal and the other lateral. This apparatus has the qualities of maximum and minimum speed and flies regularly in a line either horizontally, ascending or descending, without successive bounds and not following a sinuous line.

The invention relates to that type of aeroplane specially constructed to ensure stability in which the carrying planes are mounted upon a vertically disposed pivot or axis, or on a turntable, and are free to oscillate on the pivot, axis or turntable, independently of the body of the machine, according to the direction of the air pressure.

In such machines it has been proposed to mount the propeller on a horizontal shaft carried by the body, to provide the body with a vertical axle, and to pivot the plane horizontally on top of said axle. It has also been proposed in such machines to employ a dihedral angled plane having the tips or outer parts laterally higher than the middle.

According to the present invention the machine consists of three parts: (1) the planes, (2) the fuselage or main frame with the controlling parts, such as the horizontal and steering rudders and the landing skid, and (3) the under frame or running part carrying the propeller shaft, engine, seat and wheels. The first part may move automatically on a vertical axis with relation to the second and third parts, and the first and second parts may move automatically on a

horizontal axis with relation to the third part.

The invention is illustrated in the accompanying drawings by way of example, in which:

Fig. 1 is a front elevation of the aeroplane.

Fig. 2 is a plan thereof and Fig. 3 is a side elevation of the same.

Fig. 4 is a vertical transverse section through the two rings on the line A—B of Fig. 2.

In the drawings the same letters of reference indicate like parts.

a indicates an axle, *b* the motor, *c* an exterior ring, *d* an interior ring, *e* bearings, *f* the steering rudder, *g* the horizontal rudder, *h* part of the under carriage, *i* tension wires, *j* the running wheels, *k* the fuselage, *l* the running or landing skid, *m* the planes or wings, *n* the propeller, *o* the axle of the running wheels, *p* the seat.

The two concentric rings *c* and *d* fit one in the other with rotary movement upon balls, see Fig. 4. At each of two opposite points upon the interior ring *d* is fixed a bearing *e*, at those points where the axle *a* of the under frame or carriage engages in the said bearings.

The principal carrying surfaces *m* are of dihedral form, or very open V shaped, and sloping slightly backwards, with little wings for righting purposes. These carrying surfaces *m* are fixed upon the exterior ring *c*.

The chassis or fuselage *k* is fixed to the inner ring *d*. The under frame *h* is suspended by means of and rigidly fixed to the transverse axle *a*, the rotation of which only takes place from front to back and vice-versa. The shaft upon which is fixed the propeller *n* is mounted in bearings connected rigidly with respect to the said axle *a*. This shaft forms an angle of 90° with an imaginary line passing simultaneously through the axle *a* and the centre of gravity of the whole apparatus. It is connected direct with the rotary or other motor *b*. The

car *p* or suspension frame, with the running gear *o*, *j*, supports the pilot, the observer, the control levers, and various accessories.

The fuselage or main frame *k* carries the 5 controlling parts, that is to say, the horizontal rudder *g* and steering rudder *f*.

From this arrangement it results that the 10 principal carrying surfaces *m*, with the two rings *c*, *d*, and the fuselage *k*, have a longitudinal tilting movement in view of the changing of the angle of attack, a movement totally independent of the lower frame *h*. The wings *m* have a rotary movement with the exterior ring *c* directly independent of 15 the lower frame *h* and of the fuselage *k*. This longitudinal tilting movement is obtained by adjusting the fuselage *k*, partly by hand and partly automatically, which causes the two rings *c*, *d*, to tilt longitudinally and 20 at the same time the wings *m* attached to the exterior ring *c*. This movement is effected around the axle *a* by means of the two bearings *e* carried by the interior ring *d*.

25 The fuselage *k* has, in addition to the longitudinal tilting movement with the two wings *m*, a rotary movement with the interior ring *d*.

The under or running frame *h* has also 30 a possible longitudinal movement, but as the centre of gravity of the suspending means *h* is always below the axle *a* of attachment, its position remains invariable. The slight movement of the under or running frame 35 which might take place due to the resistance of the air, may be advantageously corrected either by a very pointed body or by a horizontal plane attached rigidly to the back part of the under frame, or by a dash pot arrangement. If the under frame swings backwards, the air acting on the upper surface of the horizontal plane will tend to 40 right the frame. If the under frame swings forwards, the air acting on the under surface of the horizontal plane will tend to 45 right the frame. Further, this possible movement, which is already small, would be diminished by the gyroscopic force of the 50 motor and of the propeller.

55 The lateral movement of the frame is controlled by the steering rudder *f*. This movement is obtained by the rotation of the fuselage *k* with the under frame *h* and interior ring *d* in the exterior ring *c*.

60 The propeller *n* has a horizontal traction which is independent of the longitudinal and lateral movements of the wings *m*. Its lateral position is, however, controlled only by the steering rudder *f*, which, as already stated, controls the lateral position of the fuselage *k*.

Automatic adjustment.

Once the horizontal rudder is fixed, the

fuselage will maintain itself in a position of 65 automatic equilibrium with the two rings and the wings, without it being possible to upset the longitudinal equilibrium, so that without further intervention of the horizontal rudder, the fuselage will retain its position and the apparatus, without any intervention, will continue to rise, descend, or to travel horizontally. 70

In like manner, once the steering rudder is fixed by the wires in the stop notches, the 75 fuselage will maintain itself in an invariable lateral position, and the apparatus will turn continually in the same curve.

Manual adjustment.

80 In order to rise more or descend more, and the inverse, or to turn more quickly, or the inverse, it is necessary to change the horizontal and steering rudders and the fuselage takes up a new corresponding position, 85 which it retains indefinitely if the controls are not changed.

The controls do not operate automatically but by manual adjustment and they are not necessary for the automatic stability of the 90 apparatus.

95 The effect due simultaneously to the direct independence of the propeller longitudinally and laterally, and to the longitudinal and lateral movement of the wings having the form herein-before described and shown in the drawings, assures the automatic longitudinal and lateral stability of the apparatus.

100 I claim:

1. In an improved aeroplane having automatic longitudinal and lateral stability, the combination of: a substantially horizontal outer ring carrying the wings; an inner ring having the fuselage secured thereto, mounted concentrically within said outer ring and capable of rotation about a central vertical axis in relation to such outer ring; a pair of diametrically opposed bearings on the underside of said inner ring; and a transverse axle, 105 carrying the propeller shaft rotatably supported in said bearings and having the under-carriage pivotally suspended thereto, said transverse axle extending at right angles to the longitudinal axis and through 110 the centre of gravity of the aeroplane; substantially as described.

2. In an improved aeroplane having automatic longitudinal and lateral stability the combination of: a substantially horizontal outer ring having an inner circular grooved recess and carrying the wings; opposed ball races formed in said circular recess; a rotatable concentric inner ring carrying the fuselage and having an outer circular flange 120 engaging the aforesaid circular grooved recess of the outer ring; two sets of steel balls 125 cooperating with the aforesaid opposed ball-

races to form ball-bearings for the two sides of the said circular flange of the inner ring; a pair of diametrically opposed bearings on the underside of said inner ring; and a

pended thereto, said transverse axle extending at right angles to the longitudinal axis and through the centre of gravity of the 10 aeroplane; substantially as described.

⁵ transverse axle, carrying the propeller shaft, rotatably supported in said bearings and having the under-carriage pivotally sus-

In testimony thereof I signed hereunto my name.

J. DEHOUCK.
